US0D1048910S

(12) **United States Design Patent** (10) Patent No.: **US D1,048,910 S**
(45) Date of Patent: ** Oct. 29, 2024

(54) **SECURITY DEVICE**

(71) Applicant: **Essence Security International (E.S.I.) Ltd**, Herzliya Pituah (IL)

(72) Inventors: **Eran Vendriger**, Herzliya Pituah (IL); **Pavel Lindberg**, Herzliya Pituah (IL); **Eran Cohen**, Herzliya Pituah (IL); **Sergey Meron**, Herzliya Pituah (IL)

(73) Assignee: **Essence Security International (E.S.I.) Ltd**, Herzliya Pituah (IL)

(**) Term: **15 Years**

(21) Appl. No.: **29/928,177**

(22) Filed: **Feb. 8, 2024**
